UNITED STATES PATENT OFFICE

93,559

DESIGN FOR A MOTOR DRIVEN TANK TRUCK

Howard W. Kizer, South Orange, N. J., assignor
to The Texas Company, New York, N. Y., a cor-
poration of Delaware

Application November 24, 1933, Serial No. 49,850

Term of patent 14 years

To all whom it may concern:

Be it known that I, HOWARD W. KIZER, a citizen of the United States, residing at 311 Self Place, in the city of South Orange, county of Essex, and State of New Jersey, have invented a new, original, and ornamental Design for a Motor Driven Tank Truck, of which the following is a specification, reference being had to the accompanying drawings, forming part thereof.

Figure 1 is a view in side elevation of a motor driven tank truck embodying my design, Figure 2 is a front end view of the same, and Figure 3 is a top plan view of the truck shown in Figure 1.

The principal and dominating feature of the present design comprises the appearance of the

central or tank portion of the truck body in which the filling cap assemblies are concealed within the shell of the tank and other normally projecting parts are either eliminated or hidden from view, as indicated by the full lines in Figures 1, 2 and 3. The minor features of the design, shown in the dotted lines, are illustrative of a type of motor driven tank truck forming the subject matter of my Design Patent No. 89,642.

I claim:

The ornamental design for a motor driven tank truck, substantially as shown and described.

HOWARD W. KIZER.
